(57) **CLAIM**

The ornamental design for an industrial robot, as shown and described.

DESCRIPTION

FIG. 1 is a first perspective view of an industrial robot showing our new design;

FIG. 2 is a second perspective view thereof;

FIG. 3 is a front view thereof;

FIG. 4 is a rear view thereof;

FIG. 5 is a right side view thereof;

FIG. 6 is a left side view thereof;

FIG. 7 is a top plan thereof; and,

FIG. 8 is a bottom plan view thereof.

The uneven-length broken line defines the bounds of the claimed design and forms no part thereof. The even-length broken line showing of the remainder of the industrial robot forms no part of the claimed design.
